DESIGN FOR A KEY BLANK

Leonard Weare Young, Moor Park, and Jack William Taylor, New Denham, England, assignors to Ingersoll Limited, London, England, a British company

Application June 2, 1947, Serial No. 139,398
In Great Britain December 4, 1946

Term of patent 14 years

(Cl. D50—4)

To all whom it may concern:

Be it known that we, Leonard Weare Young and Jack William Taylor, British subjects, residing at Moor Park, Middlesex, England, and New Denham, Buckinghamshire, England, respectively, and whose post-office addresses are Kent House, Russell Road, Moor Park, Middlesex, and "Westdean," Knighton Way Lane, New Denham, Buckinghamshire, England, respectively, have invented a new, original, and ornamental Design for a Key Blank, of which the following is a specification, reference being had to the accompanying drawing, forming part thereof.

In the accompanying drawing:

Figure 1 is a perspective view of the key blank, shown and described.

Figure 2 is a similar view but showing the opposite side of the blank;

Figure 3 is a side elevation of the same;
Figure 4 is a plan view.

The dominant features of the design reside in the key bow shown in full lines.

We claim:

The ornamental design for a key blank, as shown and described.

LEONARD WEARE YOUNG.
JACK WILLIAM TAYLOR.
